UNITED STATES PATENT OFFICE.

HENRY J. EILERS, OF PORTLAND, OREGON.

SOUNDING-BOARDS FOR PIANOS.

1,083,441.

Specification of Letters Patent.

Patented Jan. 6, 1914.

Application filed October 22, 1912. Serial No. 727,184.

To all whom it may concern:

Be it known that I, HENRY J. EILERS, a citizen of the United States, residing at Portland, in the county of Multnomah and 5 the State of Oregon, have invented certain new and useful Improvements in Sounding-Boards for Pianos, of which the following is a specification.

The object of this invention is to provide 10 two sounding-boards for a piano and provide openings leading from the top of the space between the sounding-boards to the exterior of the piano. With a secondary sounding board having ribs spaced intermediate 15 the ribs on the primary sounding-board and having openings at its center portion and the above mentioned openings, a greater resonance is secured and the volume of the music is greatly increased.

20 In the accompanying drawings: Figure 1 is a back view of a piano frame. Fig. 2 is a section on the line 2—2 of Fig. 3. Fig. 3 is a section on the line 3—3 of Fig. 2.

25 In the accompanying drawings is shown the rear frame-work of a piano that carries the sounding-boards, string-plate and plank. This frame consists of a base piece 1, an upper cross-bar 2, 3, which is carried by the upright posts 4. Secured to the upper cross-bar 2 and uprights 4 is the pin-plank 5 carrying the pins 6.

30 The primary sounding-board 7 is of suitable construction, supported by the frame, and has mounted upon it a plurality of ribs 8.

The secondary sounding-board 9 is mount-

ed parallel with the primary sounding-board, forming the inclosure 10, but does not cover the entire frame, as is clearly shown in Fig. 1. Openings 11, of any suitable design are made in the secondary sounding-board, and mounted on said board are the ribs 12, spaced intermediate the ribs 8, but not passing over the openings 11.

40 It will be noticed in Fig. 2, that the upright posts 4 are cut away so as not to contact the secondary sounding-board.

A plurality of openings 13 connect the space 10 with the above exterior of the frame. Ferrules 14 are placed at the head 50 of these openings to form a pleasing design.

I claim as my invention:

A piano comprising a primary sounding board, a secondary sounding board spaced from said primary sounding board, the inclosure intermediate the sounding boards forming a sounding chamber, and a closure for the top of said sounding chamber, the top of which closure is a portion of the piano top, said closure having openings leading 55 from the sounding chamber directly to the said top of the piano and forming sounding passages communicating with the sounding chamber and outer atmosphere.

60 In testimony whereof I have hereunto set my hand in presence of two subscribing witnesses.

HENRY J. EILERS.
